UNITED STATES PATENT OFFICE.

JOHN F. O'CONNOR, OF CHICAGO, ILLINOIS, ASSIGNOR TO WILLIAM H. MINER, OF CHICAGO, ILLINOIS.

DRAFT-RIGGING FOR RAILWAY-CARS.

1,138,139.

Specification of Letters Patent.

Patented May 4, 1915.

Application filed April 11, 1914. Serial No. 831,200.

To all whom it may concern:

Be it known that I, JOHN F. O'CONNOR, a citizen of the United States, residing at Chicago, in the county of Cook and State 5 of Illinois, have invented a certain new and useful Improvement in Draft-Rigging for Railway-Cars, of which the following is a full, clear, concise, and exact description, reference being had to the accompanying 10 drawings, forming a part of this specification.

My invention relates to improvements in draft rigging for railway cars.

The object of my invention is to provide 15 a compact, simple and efficient railway car draft rigging.

In the drawings forming a part of this specification, Figure 1 is a plan view of a draft rigging embodying my invention; 20 Fig. 2 is a vertical longitudinal section on line 2—2 of Fig. 1; Fig. 3 is a cross section on line 3—3 of Fig. 2.

Referring to the drawings, the numerals 4—4 indicate draft sills or parts of the car 25 frame to which the draft rigging is applied; 5—5 represent cheek plates, draft lugs or side castings, the same being oppositely arranged between the draft sills, and each being secured to the adjacent sill by any 30 suitable means, preferably the rivets 6—6.

The numeral 7 indicates a draw-bar, only the rear portion thereof being shown in the drawings, having a transverse slot 8 to receive the coupler-key 9, which passes through 35 slots 10 in the adjacent limbs of the draft yoke 11 and through slots 12—12 in the draft sills. Each cheek plate, draft lug or side casting 5 is provided with a preferably integral housing 13 to receive an end of the 40 shoe 14. The shoe 14 is mounted between the cheek plates, draft lugs or side castings 5—5 and is preferably of a general cylindrical shape, the lower face 15 thereof being squared and having a recess or groove 16 therein. The housing 13 at either end of the 45 shoe 14 conforms in shape to the adjacent faces of the shoe, the lower opening 17 of each housing being of a lesser width than the diameter of the shoe 14 to prevent the 50 downward displacement of the shoe. A bolt 18, or other suitable means, is passed through the shoe 14 and through suitable perforations 19 in the upper ends of the upper set 20 of plates or springs, the said plates alternating in their arrangement with the plates

or springs 21 of the lower set of springs. The lower springs 21 are received in a groove or recess 22 in the upper face of a shoe 23, which is similar in construction to the shoe 14, the lower set of plates 21 being 60 held in said recess by a bolt 24 passing through the said shoe, preferably at its middle portion. The ends of the lower shoe 23 are received in, and borne by a housing 25 at either end; each of said housings 25 consisting preferably of a separable member received within a slot 26 in the lower central portion of a cheek plate, draft lug or side casting 5. Each of said housings 25 receives an end of the shoe 23 within its appropriate 70 recess 27, the walls of said recess conforming to the adjacent bearing face of the shoe 23. The upper and lower spring plates pass through a vertical opening 30 in a block 31 which is received within the yoke 11, its 75 sides engaging the limbs 31—31 of the yoke in preferable arrangement, and its forward and rear ends preferably engaging the draw-bar 7 and the rear member 32 of the yoke 11, respectively. The front and rear walls 80 forming the opening 30 in the said block are convex, as illustrated in Fig. 2 of the drawings.

In mounting the compression-resisting parts of the draft rigging between the draft 85 sills, the upper set of springs is inserted in the shoe 14, and secured therein by the bolt 18, the said springs being passed through the opening in the block mounted within the yoke, and thereupon the lower housings 25, 90 with the lower set of springs and lower shoe 23 assembled therein, are passed into position from underneath, the lower housings then being appropriately secured to the sills and side castings preferably by the bolts 95 35—35. The upper faces 36—36 of the lower housing members 25—25 support the block within the yoke and also support the yoke, the limbs of the yoke and the block being in sliding engagement therewith in 100 the operation of the gear.

On forward movement of the draw-bar, the block within the yoke is drawn forwardly, its movement being resisted by the 105 springs passing through the block, the upper and lower sets of springs on flexing being in frictional engagement with each other, the free ends of one set moving away from the secured ends of the other set. The forward movement of the block is limited 110

by the conformation of the springs to the convex rear face forming the opening 30 through the block. During the forward movement of the draw-bar, the upper and lower shoes rotate in their respective housings.

On rearward movement of the draw-bar, the block within the yoke is moved rearwardly, the upper and lower shoes rotating 10 in their respective housings as the springs are rearwardly flexed. The frictional action between the upper and lower sets of springs occurs in a manner similar to that described upon forward movement of the draw-bar, 15 the rearward movement of the block being limited by the conformation of the springs to the convex face forming the forward wall of the opening in the block.

I claim:

20 1. In a draft rigging for railway cars, in combination, draft members, a draw-bar, cheek plates, draft yoke connected to the draw-bar, a slotted block within the draft

yoke, two sets of spring plates, upper and lower rotatable shoes, and separate housings 25 for the lower shoe, the cheek plates being provided with housings to receive the upper shoe, one set of spring plates being connected at one end to the upper shoe, the other set of spring plates being connected 30 at one end to the lower shoe.

2. In a draft rigging for railway cars, the combination with draft members having cheek plates secured thereto, of an upper shoe extending from one cheek plate to the other and mounted in bearings carried by said cheek plates, a lower shoe extending from one cheek plate to the other cheek plate and rotatably mounted in bearings carried thereby, and spring plates secured at their 40 ends in said shoes.

JOHN F. O'CONNOR.
